Primary Examiner — Marianne Pandozzi(74) Attorney, Agent, or Firm — David A. Levine(57) CLAIM

The ornamental design for a hands free beverage container, as shown.

DESCRIPTION

A portion of the disclosure of this patent document contains material to which a claim for copyright and trademark is made. The copyright and trademark owner has no objection to the reproduction of the patent document or the patent disclosure, as it appears in the U.S. Patent Office records, but reserves all other copyright and trademark rights whatsoever. FIG. 1 is a perspective view of a hands free beverage container showing our new design;

FIG. 2 is a left side view thereof;

FIG. 3 is a right side view thereof; and,

FIG. 4 is a front view thereof.

The broken lines in the drawings are included for the purpose of illustration and form no part of the claimed design.
